CLAIM

The ornamental design for a fluid distribution equipment, as shown and described.

DESCRIPTION

FIG. 1 is a perspective view of a fluid distribution equipment showing my new design;

FIG. 2 is a top view thereof;

FIG. 3 is a bottom view thereof;

FIG. 4 is a front view thereof;

FIG. 5 is a back view thereof;

FIG. 6 is a left-side view thereof;

FIG. 7 is a right-side view thereof;

FIG. 8 is a partial sectional view of an exemplary configuration of the fluid distribution equipment; and,

FIG. 9 is a sectional view of the exemplary configuration of the fluid distribution equipment.

The broken lines in the drawings depict portions of the fluid distribution equipment and environment that form no part of the claimed design.
